[57] CLAIM

The ornamental design for a decorator rod pulley housing, as shown and described.

DESCRIPTION

FIG. 1 is a front perspective view of a decorator rod pulley housing showing my new design;

FIG. 2 is a rear perspective view thereof;

FIG. 3 is a section taken along line 3—3 of FIG. 2;

FIG. 4 is a left side elevation view thereof, the right side elevation view being a mirror image; and

FIG. 5 is a top plan view thereof.

FIG. 1

FIG. 2

FIG. 3

FIG. 4

FIG. 5
